MOUNTING FOR REFLECTOR BUTTONS

Harold R. Schutz, Ottawa Hills, Ohio, assignor
to Libbey Cataphote Corporation, Toledo, Ohio,
a corporation of Ohio

Application April 28, 1934, Serial No. 722,922

2 Claims. (Cl. 88—82)

This invention relates to an improvement in a mounting means for autocollimators or reflecting buttons of the lens mirror type in which an incident ray of light is refracted and reflected back to its source or substantially so. A plurality of such autocollimators are mounted on a panel to form a character or sign which is visible at night to automobile passengers, due to the rays of the automobile headlights being reflected back to the automobile. This invention is directed specifically to a mounting by which such buttons are held on the panel.

The primary object is to provide a mounting that will securely hold a button in position on a panel and will protect the button from unauthorized removal.

Another object is to provide such a mounting which is simple and inexpensive to manufacture and which is easily applied to a panel.

Still a further object is to provide such a mounting which will insure a reflector button being mounted with its axis aligned with the housing and perpendicular to the panel.

Other objects will be apparent from the following description.

In the drawing:

Fig. 1 is a central longitudinal sectional view of such a mounting mounted on a panel with a reflector button.

Fig. 2 is a perspective view of the outer shell of the mounting split in half longitudinally.

Fig. 3 is a perspective view of the inner shell of the mounting.

In detail 1 is a cylindrical glass reflector button having an objective lens 2 and a reflecting rear surface 3 and provided with a circumferential shoulder 4 adjacent its objective lens 2. The button is further provided with an oppositely disposed circumferential shoulder 5 positioned slightly to the rear of a point midway between the objective lens 2 and the reflecting surface 3.

The mounting proper comprises an inner cylindrical shell 6 provided with threads 7 adjacent its closed rear end and has an outwardly projecting rim 8 that is folded back upon itself to form an inwardly projecting rim 9. Two outwardly bent prongs 10 are cut from the sides of the inner shell 6 as is clearly shown in Fig. 3.

The outer shell 11 is of slightly larger diameter and is provided with threads 12 adapted to cooperate with the threads 7 of the inner shell. The sides of the outer shell 11 at a point forward of the threads 12 are formed with an outward bend 13 and an upward bend 14 resulting in the upper diameter of the shell being greater

than the base diameter. The edge 15 of the rim is turned outwardly at right angles to the plane of the side of the shell to form a flat bearing surface 16.

In operation the reflector button of the shape described is placed within the inner shell 6 with a circular pliable gasket 17 abutting the shoulder 5 and with its object lens 2 exposed, its central side portion abutting the side of the shell to insure correct alignment, and the rim of the shell is folded down over the shoulder as at 9, thus holding the button securely within the inner shell, the gasket 17 compressed between the shoulder 5 of the button and the reduced or threaded portion 7 of the shell. A circular hole 18 is then provided in the desired position on the panel 19 having a diameter only slightly greater than that of the inner shell. The button mounted in the inner shell is then pushed through this hole until the inwardly projecting rim 9 rests against the outer surface of the panel 19. As this is done the prongs 10 bend inwardly as they are forced through the hole and then snap out to normal position as shown in Fig. 1. The outer shell 11 is then threaded onto shell 6 and tightened until bearing surface 16 contacts the inner surface of the panel which then becomes clamped between surface 16 and rim 9. It will be noted that the upper part of outer shell 11 is enlarged to provide clearance for the spring 20 prongs 10 of the inner shell. It is customary to provide a backing panel which will enclose the rear portion of the assembly and it is therefore apparent that unauthorized removal from the front is not permitted by the prongs 10 which act as barbs. The assembly can only be removed from the rear of the panel by unscrewing the outer shell and then compressing the prongs and pushing the inner shell out through the hole.

I claim:

1. A reflector button mounting comprising a button encasing member, outer threads formed at the lower end thereof, an outwardly extending shoulder at the upper end, upwardly directed compressible prongs extending outwardly from the side of said member above the threads adjacent and opposing said shoulder to form stop members, a hollow clamping member, inner threads formed at the lower end thereof, the wall of said casing member being formed outwardly and upwardly above said inner threads to provide a housing for said prongs when said two members are threaded together and a bearing surface formed at the rim of said clamping member.

2. A mounting assembly to be mounted within a circular opening in a panel and adapted to hold a reflector button comprising a button encasing member, outer threads formed at the lower end thereof, an outwardly extending shoulder at the upper end, upwardly directed compressible prongs extending outwardly from the side of said member above the threads and adjacent said shoulder to oppose the rear of the panel, said encasing member adapted to be positioned within the circular opening in the panel, the lower end extending rearwardly, the shoulder abutting the panel front, the prongs adjacent and opposing the rear of the panel to prevent removal.

al of the encasing member from the front of the panel, a hollow clamping member, inner threads formed at the lower end thereof, the wall of said casing being formed outwardly and upwardly above said inner threads to provide a 5 housing for said prongs, a bearing surface formed at the rim of said clamping member, said clamping member adapted to be threaded onto said encasing member until said bearing surface contacts the rear of the panel to clamp the 10 panel between it and the shoulder of the encasing member thus securing the button in position and encasing the prongs.
